UNITED STATES PATENT OFFICE

ARTHUR R. MCARTHUR, OF GARY, INDIANA, ASSIGNOR TO AMERICAN SHEET AND TIN PLATE COMPANY, OF PITTSBURGH, PENNSYLVANIA, A CORPORATION OF NEW JERSEY

PREHEATER

Application filed January 14, 1928. Serial No. 246,877.

This invention relates to preheaters for fluids used to promote combustion in heating furnaces and, while not limited in any way thereto, is illustrated in connection with, 5 and is particularly adapted for, use with a continuous pack heating furnace for heating sheets and packs of sheets.

One object of the present invention is to provide a preheater which will serve to conduct 10 the products of combustion from the work discharge port of the furnace to a stack so as to prevent the discharge of said products of combustion into the mill, and at the same time will utilize said products of combustion 15 to preheat the fluids used to promote the combustion in the furnace.

Another object is to provide a novel form of preheater including a flue portion adapted to receive the cold or atmospheric air drawn 20 into said preheater and to prevent said cold or atmospheric air from coming into contact with the conduits containing the fluids to be preheated.

A further object is to provide a preheater 25 having the novel construction, design and arrangement of parts hereinafter described and illustrated in the accompanying drawings.

In the drawings—

30 Figure 1 is a longitudinal sectional elevation through a pack heating furnace having the preheater of this invention applied thereto.

Figure 2 is an enlarged front elevation of 35 the preheater.

Figure 3 is a sectional plan taken on the line III—III of Figure 2.

Figure 4 is a vertical sectional elevation 40 on the line IV—IV of Figure 3.

Figure 5 is a sectional side elevation through the preheater.

Figure 6 is a fragmentary detail showing 45 the manner in which the preheater tubes are connected to the manifolds.

Referring more particularly to the drawings, the numeral 2 designates the furnace as a whole, which has a combustion chamber 3 along one side from which the products of 50 combustion are adapted to be delivered to the

interior of the furnace proper which comprises a heating chamber 4.

A charging port 5 is formed in the rear end of the furnace and an exit or discharge port 6 is provided in the forward end of the 55 furnace through which the material or work to be heated is charged and discharged, respectively. A conveyer consisting of a plurality of conveyer rollers 7 is provided in the furnace for conveying the work through the 60 furnace.

In operation, the products of combustion pass from the combustion chamber 3 into the heating chamber 4 and take on a swirling or centrifugal motion, which causes them to 65 travel forwardly through the furnace and pass out of the discharge port 6. During the travel of the products of combustion through the furnace the work-pieces being conveyed through the heating chamber 4 will be heated. 70

The furnace proper forms the subject matter of a separate application for patent and, therefore, will not be further described or illustrated in detail in this application.

In order to prevent the waste products of 75 combustion from escaping into the atmosphere of the mill and at the same time to utilize the heat of said waste products, a preheater A is mounted on the forward end of the furnace immediately above the discharge 80 port 6.

The preheater A comprises an outer substantially rectangular shell 9 having its upper end closed by a wall 10 and its lower end open to receive the products of combustion from 85 the furnace discharge port 6.

A stack 12 is mounted above the furnace 2 and the preheater A has its upper end connected to the stack 12 by a flue 14.

Manifold shells 15 and 16 are mounted 90 along the respective sides of the shell 9 to form manifold chambers 17 and 18, respectively. An inlet conduit 19 for the air or other fluid to be preheated communicates with the upper end of the manifold chamber 15, 95 and an outlet conduit 20 communicates with the lower end of the manifold chamber 16 to conduct the preheated fluid to the burner 21, indicated in Figure 1.

A transverse partition wall 22 extends be- 100

tween the manifold shells 15 and 16 in a plane parallel with the front wall of the outer preheater shell 9 so as to divide the interior of the shell 9 into a flue portion 23 and preheating chamber 24. The wall 22 terminates short of the upper and lower ends of the shell 9.

A plurality of preheater conduits or tubes 25 extend transversely of the preheating chamber 24 and have their ends communicating with the respective manifold chambers. The manifold chambers 17 and 18 are divided into sections by dividing walls 26 and 27, respectively, so as to cause the fluid to be preheated to flow back and forth through respective groups of the conduits 25.

In the specific embodiment of the invention illustrated thirty-six tubes are used, arranged in transverse rows of three tubes each. The wall 26 is mounted in the manifold chamber 17 between the fourth and fifth rows of tubes from the top, and the wall 27 is mounted in the manifold chamber 18 between the eighth and ninth rows of tubes from the top, so that the tubes are divided into three groups of twelve tubes each.

The air or other fluid will enter the manifold chamber 17 through the conduit 19 and will pass through the uppermost group of tubes 25 into the manifold chamber 18. The fluid will then flow in the reverse direction through the next lower group of tubes 25, into the portion of the manifold chamber 17 below the wall 26. The flow of fluid will again be reversed in direction and flow through the lowermost group of tubes 24, into the portion of the manifold 18 below the wall 27, and the fluid will then pass from the manifold chamber 18 through the conduit to the burner 21.

In operation, the flames and other products of combustion pass from the discharge port 6 of the furnace 2 and are drawn up through the preheater shell 9, due to the natural draft created by the stack 12. The preheater shell 45 is so proportioned and the wall 22 is so positioned that the major portion of the flames and products of combustion will pass upwardly through the preheating chamber 24 and only a very small proportion thereof will pass into the flue portion 23 forward of the wall 22.

Due to the draft created by the stack, the atmospheric air will be drawn into the preheater shell. However, due to the wall 22, the major portion of such air will be drawn up through the flue portion 23 and, therefore, will not come in contact with the tubes 25, so that a higher temperature is maintained around the tubes 25 than would be possible if the cold air were permitted to intermingle with the products of combustion in the preheating chamber.

While I have shown and described one specific embodiment of my invention, it will be understood that I do not wish to be limited

thereto since various modifications may be made without departing from the scope thereof, as defined in the appended claims.

I claim—

1. The combination with a heating furnace having a discharge port through which the material being heated is discharged and through which the products of combustion pass from the furnace, of a preheater located at the discharge end of said furnace immediately above said discharge port, said preheater comprising a shell having an open lower end and a closed upper end, a transverse partition wall in said shell dividing said shell into a flue portion along the front wall and a preheater chamber between said flue portion and the rear wall of said shell, a manifold chamber formed at each side of said shell, a plurality of conduits extending transversely of said shell and communicating with said manifold chambers, an inlet port in one of said manifold chambers for the fluid to be preheated, an outlet port in the other of said manifold chambers for the preheated fluid, a stack, and means connecting the upper end of said shell and said stack, whereby a draft is created to cause the products of combustion to flow upwardly from said discharge port through said shell, said flue portion along the front wall of said shell being adapted to receive the cold air drawn into the preheater by the draft created by said stack and also to receive at least a part of the products of combustion from said furnace.

2. The combination with a heating furnace having a discharge port through which the material being heated is discharged and through which the products of combustion pass from the furnace, of a preheater located at the discharge end of said furnace immediately above said discharge port, said preheater comprising a shell having an open lower end and a closed upper end, a transverse partition wall in said shell and terminating short of the ends thereof, said partition wall dividing said shell into a flue portion along the front wall and a preheater chamber between said flue portion and the rear wall of said shell, a manifold chamber formed at each side of said shell, a plurality of conduits extending transversely of said shell and communicating with said manifold chambers, an inlet port in one of said manifold chambers for the fluid to be preheated, an outlet port in the other of said manifold chambers for the preheated fluid, a stack, and means connecting the upper end of said shell and said stack, whereby a draft is created to cause the products of combustion to flow upwardly from said discharge port through said shell, said flue portion along the front wall of said shell being adapted to receive the cold air drawn into the preheater by the draft created by said stack and also to receive at least a part of the products of combustion from said furnace.

3. The combination with a heating furnace having a discharge port through which the material being heated is discharged and through which the products of combustion pass from the furnace, of a preheater located at the discharge end of said furnace immediately above said discharge port, said preheater comprising a shell having an open lower end and a closed upper end, a transverse partition wall in said shell dividing said shell into a flue portion along the front wall and a pre-heater chamber between said flue portion and the rear wall of said shell, a manifold chamber formed at each side of said shell, a plurality of conduits extending transversely of said shell and communicating with said manifold chambers, an inlet port in one of said manifold chambers for the fluid to be pre-heated, an outlet port in the other of said manifold chambers for the preheated fluid, means for dividing said manifold chambers so as to cause the fluids to be preheated to flow alternately in opposite directions through groups of conduits, a stack, and means connecting the upper end of said shell and said stack, whereby a draft is created to cause the products of combustion to flow upwardly from said discharge port through said shell, said flue portion along the front wall of said shell being adapted to receive the cold air drawn into the preheater by the draft created by said stack and also to receive at least a part of the products of combustion from said furnace.
- 35 4. The combination with a furnace having a discharge port through which the products of combustion pass from the furnace, of a preheater located outside of said furnace and immediately above said port, said preheater comprising a shell having its lower end open to receive the products of combustion and having an opening adjacent its upper end through which the products of combustion escape, a transverse partition wall in said shell dividing said shell into a flue portion along the front wall and a preheater chamber between said flue portion and the rear wall of said shell, a manifold chamber formed at each side of said shell, a plurality of conduits extending transversely of said shell and communicating with said manifold chambers, means for admitting fluid to be heated to one of said manifolds, and means for permitting the discharge of the heated fluid from the other of said manifolds, said flue portion along the front wall of said shell being adapted to receive the cold air drawn into the preheater by the draft through said preheater and also to receive at least a part of the products of combustion from said furnace.

In testimony whereof I have hereunto set my hand.

ARTHUR R. McARTHUR.
